DESIGN FOR A HAT

John Cavanagh, Norwalk, Conn., assignor to Hat Corporation of America, Norwalk, Conn., a corporation of Delaware

Application August 19, 1935, Serial No. 58,205

Term of patent 14 years

To all whom it may concern:

Be it known that I, John Cavanagh, a citizen of the United States, residing at Norwalk, in the county of Fairfield and State of Connecticut, have invented a new, original, and ornamental Design for a Hat, of which the following is a specification, reference being had to the accompanying drawing, forming a part thereof, and in which:—

Figure 1 is a front view of the hat.

Figure 2 is a side view of the hat embodying my design.

Figure 3 is a fragmentary top plan view showing a brim which on the top is flat to its outer edge and substantially at a right angle to the crown, of approximately one-half the hat, the

remaining half, not shown, being substantially the same.

Figure 4 is a fragmentary bottom plan view of the hat showing the tapering outer edge.

The design is characterized by a thick brim having a substantially even thickness extending to a point near its outer edge and there having a tapering surface extending from the bottom toward the top of the brim, ending in a comparatively thin outer edge.

I claim:

The ornamental design for a hat, substantially as shown and described.

JOHN CAVANAGH.
